UNITED STATES PATENT OFFICE

2,041,350

MECHANICAL PUDDLER

Marvin O. Johnson, Milwaukee, Wis., assignor to
 Koehring Company, Milwaukee, Wis., a corporation

Application March 21, 1931, Serial No. 524,393

5 Claims. (Cl. 94—44)

In the laying of roads, pavements, and the like, it is obviously necessary that the road material, such as concrete, be uniformly and evenly distributed over the roadbed, this even distribution being required both for the concrete employed on the sub-grade, and for the top layer of concrete which is laid over the steel reinforcing members disposed in the concrete base.

For the assurance of such even distribution with a minimum of labor and trouble, it is proposed, in accordance with this invention, to provide a power driven machine which is propelled by a source of power over a sub-grade or surface being worked upon, the usual road forms acting as rails along which the machine travels.

The present machine is also characterized by the fact that the spreading of the road material is accomplished by the use of a pair of screw conveyors the respective pitches of the vanes of which are opposite, one conveyor transporting the road material from the center of the roadway towards the lateral road forms while the other conveyor acts to bring the material to a common center, so that by operating the machine backwards and forwards on the road form rails a batch of aggregates deposited between the conveyors will be very quickly and uniformly distributed, by permitting dual transverse displacement of the material; and by providing instrumentalities for adjusting the amount of clearance of the conveyors the machine is made applicable to different stages of road building, as for the distribution of both the material for the base and for the top layer.

A further object of this invention is to provide instrumentalities permitting the operator of the machine to raise and lower the above-mentioned screw conveyors either individually or both together which assists the distribution of the road material should it be, for any reason, deposited at the side of the road or near the road forms; in such circumstances the distribution of the deposited material will be accomplished by either raising the outwardly distributing conveyor out of contact with the batch and driving the inwardly distributing conveyor into the batch, or else by keeping the conveyors at the same level and maintaining the outwardly distributing conveyor out of contact with the batch. A most efficient final distributing action will be had by keeping the conveyors at the same level and moving the machine back and forth over the roadway.

Illustrative mechanism and instrumentalities for accomplishing the above, and further, objects will be described in detail hereinafter; and it will be apparent that the machine will effectively distribute and strike off materials of many different characters, whether coarse or fine, and while it will be described primarily in connection with the building of a concrete road or pavement, it will

be understood that the machine will operate effectively on any other kind of road building material including gravel or asphalt.

In the following drawings there is illustrated a type of machine embodying, in convenient form, the features of this invention, in which drawings

Fig. 1 is a plan view of the machine.

Fig. 2 is a front elevation thereof, certain parts being omitted.

Fig. 3 is a side view.

Fig. 4 is a horizontal section through the drive mechanism showing a portion thereof.

Fig. 5 is a detail view showing instrumentalities for raising and lowering the distributing conveyors and

Fig. 6 is a sectional view taken on the line 6—6 of Fig. 5.

Referring more particularly to the drawings, the machine comprises the frame A, housing B which contains the driving mechanisms, and the distributing conveyors C and D which are slidably carried on the frame A, and which are rotated from a source of power in the housing B, which source of power also operates the various other driven instrumentalities which comprise the unitary machine.

This source of power is indicated at 10 and is conveniently an internal combustion engine having a drive shaft 11 carrying with it the rotating sleeve 12, the shaft 11 being provided with a sprocket wheel 13 and the sleeve 12 being provided with a sprocket wheel 14. By means of the driving chain 15 and sprocket wheel 16 on the shaft 17, this shaft is rotated, the motion of the shaft 17 being transmitted to the shaft 18 through engagement of suitable clutch instrumentalities indicated at 19 (see Fig. 4). This clutch 19 is operated by the clutch lever 20, which in turn is operated by the rod 21 actuated by the lever 22 which is controlled by an operator of the machine.

The shaft 18 carries a sprocket wheel 23 over which passes a chain, or other suitable driving means, 24, which engages a sprocket 25 on the distributor shaft C to drive this shaft.

Conveying distributor shaft C (see Fig. 1) is provided with a second sprocket 26 which engages a driving chain, or other suitable driving means, 27, which passes over a sprocket 28, similar to sprocket 26, carried by the conveying distributor shaft D by which motion is transmitted from shaft C to shaft D.

It may be here noted that while the driving instrumentalities specifically illustrated and described herein are stated to include sprocket 55 wheels and chain drives, obviously any other types of power transmitting mechanism, such for instance, as pulleys and belts, or other analogous devices, may be readily employed as mechanical equivalents to the sprocket and chain drives.

The conveying distributors are provided with the spirally arranged vanes 29 on shaft C and 30 on shaft D; and it will be observed that the vanes 29 and 30 are pitched in opposite directions 5 to assure distribution of the paving material in opposite directions, either from the center of the road-bed towards the sides thereof, or from the sides towards a common center.

As has been mentioned above, under certain 10 conditions it is desirable to be able to elevate these distributors C and D, either selectively or simultaneously. The mechanism for doing this will now be described.

As will be seen best from Fig. 4, surrounding the 15 shaft 17 is the hollow shaft 30', carrying the sprocket wheel 31 driven by a chain 32 (Fig. 2) engaging therewith and passing over the sprocket wheel 14 on the sleeve 12. The hollow shaft 30' is rotatable independently of the shaft 17, and 20 carries a clutch member 33 actuated by the clutch lever 34 and rod 35 operated by a hand lever 36 under control of the operator of the machine.

The clutch member 33 is the usual type of friction clutch and when the parts thereof are engaged, motion is transmitted to the sprocket wheel 37 and chain 38, which drives a sprocket wheel 39 for rotating the shaft 40. This shaft 40 has at 25 each end a bevelled gear 41 and 41a (see Fig. 1) co-acting respectively with the bevelled gears 42 and 42a on the shafts 43 and 43a, respectively, which shafts transmit the power required for raising and lowering the conveying distributor D. As the shafts 43 and 43a are duplicates of each 30 other, and since duplicate raising and lowering means are provided for each end of the distributor D, only one of these elements need be described in detail.

As mentioned above, one end of shaft 43 is provided with a bevelled gear 42 which is in engagement with the gear 41. The other end of shaft 43 is provided with a similar bevelled gear 44 which engages a vertically disposed bevelled gear 45 (see Fig. 5 for details of construction) on the end of the threaded shaft 46. The end of the shaft D' of the distributor D is journalled in a block 47 which is shaped as indicated in Fig. 6 to slide in the guide 48 as the shaft 46 is rotated. The guide 48 is mounted on the frame A of the machine. For reversing the rotation of the shaft 45 there is provided the transmission 49 (Fig. 2) at the engine which is provided with the usual type of forward and reversing gears for correspondingly operating the hollow shaft or sleeve 12 from which motion is transmitted to the hollow shaft 30' and shaft 40 as above described. It will therefore be seen that as the gear 45 and shaft 46 are driven forwardly and reversely the distributor D will be correspondingly raised and lowered by the journal block 47 riding up and down in the guide member 48. As has been mentioned above, similar instrumentalities are provided at the other end of the distributor D, so that the distributor is uniformly raised and lowered.

The transmission 49 is operated by the lever 50 under the control of the operator of the machine. There is also provided a clutch 51 for transmitting power from the engine 10 to the shaft 11 and therefore sleeve 12 rotating therewith, clutch 51 65 being operated by lever 52.

For adjusting the position of the distributor C there is provided mechanism entirely similar to that already described in connection with the distributor D. For adjusting the position of the distributor C, the hollow shaft 30' (Fig. 4) is

provided with still another clutch 53 operated by the clutch lever 54 and rod 55, which is operated by a lever 56. Engagement of the clutch elements of clutch 53 drives the sprocket wheel 57 which carries the chain 58 which engages the sprocket 5 wheel 59 on the shaft 60. Shaft 60 is similar to shaft 40, previously described, and serves a similar purpose; it is positioned, as shown, rearwardly of the shaft 40, and is supported together with shaft 40 in the supporting members 61 and 61a 10 carried by the frame of the machine. The shafts 60 and 40 are journalled through the members 61 and 61a on suitable bearings, as will be evident.

The shaft 60 is provided at its respective ends with the bevelled gears 62 and 62a which engage 15 the corresponding bevelled gears 63 and 63a on the shafts 64 and 64a. These shafts terminate in gears 65 and 65a, respectively, which operate the gears 66 and 66a on threaded shafts, exactly as above described; and through the provision of similar journal blocks for receiving the ends of the shaft C' of the distributor C, which blocks slide in guide members entirely similar to that shown at 48, the distributor C is raised or lowered as desired; and it will be seen that the distributors C and D are adjustable independently 20 of each other.

It is very desirable that the machine be made self-propelling. For this purpose there are provided flanged wheels, mounted in pairs 67 and 67a 30 on shafts 68 and 68a, respectively. Shafts 68 and 68a are provided with sprockets 69 and 69a with which the chain 70 engages, whereby motion is transmitted from the shaft 68 to shaft 68a to 35 facilitate propulsion of the vehicle, the shaft 68 being driven from the engine 10 in the following manner:

Positioned upon the hollow shaft 30' is the clutch 71 operated by the clutch lever 72, rod 73 and lever 74. Operation of the clutch 71 to engage its members transfers motion to a sprocket 75 carrying the chain 76 to drive the sprocket 77 and shaft 78, which is journalled in suitable bearings as shown in Fig. 4. The shaft 78 carries the sprocket 79 which drives the chain 80 which 45 engages a sprocket at 81 on the shaft 68 to drive this shaft and accordingly the pair of wheels 67. Power is transmitted from the shaft 68 to the shaft 68a through the chain drive 70, as previously described to facilitate propulsion of the 50 pair of wheels 67a mounted on the shaft 68a.

The wheels 67 and 67a are shown as running on the road forms 82 and 82a which are placed upon the prepared subgrade 83. To accommodate the machine for varying widths of subgrades, it is desirable to make the wheels 67 and 67a adjustable with reference to their respective shafts. This is accomplished by providing each wheel with set screws 84 and 84a, or similar releasable means, so that when desired the distance 60 between the wheels of each pair may be adjusted by sliding the wheels along the shafts. Also, to permit such adjustment to be effective, the conveyor vanes 29 and 30 are terminated short of the ends of their respective shafts C' and D', since 65 these vanes dip below the level of the tops of the side forms.

There are also carried by the frame the adjustable strike off blades or screeds 85 and 85a, the height of which may be adjusted by suitable 70 positioning of bolts 86 and 86a. These screeds are desirably positioned at both the front and rear ends of the machines, and assist in the forward movement of the material being distributed, reliance being placed upon the distributing con- 75

veyors for transverse distribution. Should the subgrade be covered with a number of batches of concrete from transit mixers, or other materials, the construction will permit the operator to drive 5 the machine over the various batches after raising the distributing conveyors, the screeds then causing the preliminary longitudinal spreading action, either screed being used as desired. Obviously, any suitable means for adjusting the position 10 of the screeds can be employed in place of the bolts, as desired; and as a matter of fact, if desired, the screeds may be raised and lowered by the provision of mechanism like that previously described for raising and lowering the conveyors. 15 For simplicity, however, the adjustment of the screeds as indicated by the bolts is shown on the drawings.

From the above description it will be seen that there is an individual drive to each of the moving parts and that the movement of the machine over the roadway is not dependent upon the operation of any other moving part. The adjustment of the machine to accommodate varying widths of subgrade and the raising and lowering 25 of the conveyors enable the operator to adapt the machine to any situation which may be encountered in actual operation.

To facilitate access to and operation of the machine there may be mounted a platform upon 30 the framework A, a fragment of which platform is indicated at 87.

It will be apparent that many details in the construction of the machine may be varied from the above illustrated form without departing 35 from the inventive concept; and it will accordingly be understood that it is intended and desired to embrace within the scope of this invention such modifications and changes as may be necessary to adapt it to varying conditions and uses.

40 Having thus described my invention, what I claim as new and desire to secure by Letters Patent in the United States, is:

1. A machine of the character described, comprising the combination with a frame, of distributors adapted to convey road materials deposited on a roadway towards and away from a common center, vertical guide members secured to the frame and oppositely disposed on opposing ends of the frame, a block slidingly mounted in each 45 guide, each distributor including a shaft having its ends journaled in opposing blocks, means to raise and lower the blocks in the guides for vertical adjustment of the shaft, a source of power, and means for transmitting motion from the 50 source of power to the adjusting means for predeterminedly positioning the vertical adjustment of the shaft, and instrumentalities carried by the shafts for operating upon a surface for suitable conditioning thereof.

60 2. A machine of the character described, comprising the combination with a frame, of distributors adapted to convey road materials deposited on a roadway towards and away from a common center, oppositely disposed vertical guide members on the frame, a block slidingly mounted in each guide, the distributors including shafts having the ends thereof journaled in each pair of opposing blocks, means for selectively raising and lowering the blocks in the guides for selective 65 vertical adjustment of the shafts for positioning either shaft into inoperative and operative positions, a source of power on the frame, driving

means from the source of power for revolving the shafts, means independent of the driving means but operated from the source of power for predeterminedly positioning the vertical adjustment of the shafts, the said means comprising independently operable instrumentalities for adjusting either shaft and means for selectively operating the said instrumentalities whereby either shaft may be adjusted independently of the other. 5

3. A machine of the character described, comprising the combination with a frame, of a pair of oppositely acting distributors for distributing road materials on a road bed, a source of power, means actuated by the source of power for selectively moving the distributors in a vertical direction, driving mechanism for the distributors, traction devices for the machine adapted to run on usual road forms as tracks, the said traction devices being adjustably mounted to accommodate varying widths of roadway, the said means for selectively moving the distributors comprising cooperating driving shafts actuated by the said source of power, vertically acting shafts driven by the said cooperating shafts, a carrying member provided at each end of the distributors operated by the said vertically actuated shafts, and guides for the said carrying members for guiding the same for vertical movement of the distributors, each of the distributors comprising a shaft and distributing vanes on the shaft but terminating short from the ends thereof for allowing for adjustment of the said traction devices. 10 15 20 25

4. A machine of the character described, comprising the combination with a mobile frame, of a pair of oppositely acting distributors for distributing road building materials deposited on a road bed incident to movement of the machine over the deposited materials, each of said distributors including a shaft rotatably mounted in the frame and extending transversely of the road bed, with distributing vanes spirally disposed about said shaft, the vanes of one distributor being pitched to move the said road materials in a direction from the opposite edges of the road bed inwardly toward the center thereof, and the vanes of the other distributor being pitched to move the said road materials in a direction from the center of the road bed outwardly toward the edges thereof, and instrumentalities for rotating said distributor shafts. 35 40 45 50

5. A machine of the character described, comprising the combination with a mobile frame, of a pair of oppositely acting distributors for distributing road building materials deposited on a road bed incident to movement of the machine over the deposited materials, each of said distributors including a shaft rotatably mounted in the frame and extending transversely of the road bed, with distributing vanes spirally disposed about said shaft, the vanes of one distributor being pitched to move the said road materials in a direction from the opposite edges of the road bed inwardly toward the center thereof, and the vanes of the other distributor being pitched to move the said road materials in a direction from the center of the road bed outwardly toward the edges thereof, instrumentalities for rotating said distributor shafts, and instrumentalities for selectively and independently elevating and lowering said distributors. 55 60 65 70

MARVIN O. JOHNSON.
